(57) **CLAIM**

The ornamental design for a yoga block, substantially as shown and described.

DESCRIPTION

FIG. 1 is a front perspective view of a yoga block in accordance with the present invention;

FIG. 2 is a front view thereof, the rear view being a mirror-image of the front view and therefore not depicted;

FIG. 3 is a left side view thereof, the right side view thereof being a mirror-image of the left side view thereof and therefore not depicted; FIG. 4 is a top view thereof; and,

FIG. 5 is a bottom view thereof.
